UNITED STATES PATENT OFFICE.

RUDOLPH G. SCHUTZ, OF PROVIDENCE, RHODE ISLAND.

SEAMLESS PLATED TAPER AND METHOD OF MAKING SAME.

962,985.

Specification of Letters Patent. Patented June 28, 1910.

Application filed August 3, 1907. Serial No. 386,931.

To all whom it may concern:

Be it known that I, RUDOLPH G. SCHUTZ, of Providence, in the county of Providence and State of Rhode Island, have invented 5 certain new and useful Improvements in Seamless Plated Tapers and Method of Making Same; and I do hereby declare the following specification, taken in connection with the accompanying drawings, forming a 10 part of the same, to be a full, clear, and exact description thereof.

The invention relates to seamless plated tapers for use in the manufacture of certain articles of jewelry, and is especially adapted 15 for use in the manufacture of seamless plated spectacle-bridge tapers and seamless plated ring tapers. Heretofore in the manufacture of such tapers a piece of solid round seamless plated wire has been used, and the end 20 portions reduced by hammering the same in a swaging machine. When manufactured in this manner the precious metal upon the outside of the end portions of the taper becomes greatly reduced in thickness and 25 considerably thinner than upon the central portion, by reason of the fact that said metal is hammered upon a solid core and can only spread lengthwise or longitudinally. This 30 is very objectionable, as it leaves the very portion of the finished spectacle-bridge, as well as the ring, which receives the greatest amount of wear with the least amount of gold and weaker at the very point where 35 greatest strength is desired.

It is the object of the present invention to overcome these objections and provide a seamless plated taper having the precious metal thicker at the end portions than at the 40 central portion thereof.

To this end the invention consists in the novel construction and method of making the same hereinafter described and claimed, reference being had to the accompanying drawings in which—

Figure 1 is a longitudinal sectional view of a blank from which my improved taper is formed. Fig. 2 is a transverse sectional view of the same. Fig. 3 is a longitudinal sectional view of the blank with both ends drilled. Fig. 4 is a transverse sectional view of one of the ends of the blank shown in Fig. 3. Fig. 5 is a longitudinal sectional view of a taper formed from the blank shown in Fig. 3. Fig. 6 is a plan view of the finished taper after it has been flattened to form a spectacle-bridge taper. Fig. 7 is

a vertical section on the line $y-y$, Fig. 6. Fig. 8 is a vertical section on the line $x-x$, Fig. 6. Fig. 9 is a longitudinal sectional view of a modified form of blank. Fig. 10 60 is a vertical section of one of the ends of Fig. 9. Fig. 11 is a longitudinal section of a taper formed from the blank shown in Fig. 9. Figs. 12 and 13 are a front and side view respectively of the finished spectacle- 65 bridge.

Referring to the drawings, the method of making my improved taper is as follows: A short piece of plated wire composed of a solid base metal core and a seamless shell 70 of precious metal 2 united to said core, as shown in Figs. 1 and 2, is drilled longitudinally at both ends forming the hollow end portions 3 and the solid central portion 4, as shown in Fig. 3. The blank thus formed 75 is then hammered down by a swaging machine until the hollow end portions 3 become practically solid. While said blank is undergoing this operation the precious metal covering the central or solid portion 4 of the 80 blank becomes a trifle thinner than it was originally, by reason of the fact that this portion of said blank is solid and when reduced in diameter, the precious metal can only spread or flow longitudinally or lengthwise of the blank. The effect of the hammering by the swaging machine upon the end portions 3 of the blank, however, is different and results in the precious metal covering these portions of said blank becoming 85 90 thicker than it was originally, by reason of the fact that these portions of the blank are hollow, and when reduced in diameter by hammering the precious metal will spread or flow transversely, as well as longitudinally, and therefore become thicker. The 95 hammering operation will also provide the same effect upon the base metal core of the blank, the central or solid portion of which will become thinner, while the end or hollow portions will become thicker and the blank will assume the form shown in Fig. 5 when it leaves the swaging machine. When the taper thus formed is to be used for a 100 spectacle-bridge taper, said taper is then flattened by dies to the form shown in Figs. 6, 7 and 8, and is then bent up into its finished form as shown in Figs. 12 and 13.

As will be seen, the increase in the thickness of the precious metal comes at that part 110 of the finished bridge which receives the most wear, viz., the sharp bends at the ends

of the U-shaped central portion, and said increased thickness also gives additional strength and spring to this portion of the bridge which is very desirable.

5 Fig. 9 shows a modified form of blank in which the base metal core is in the form of a tube 1', and a plug 5 is inserted in the central portion of said tube 1' and preferably united thereto by solder or in any other suitable manner. With this construction the end portions 3 are hollow and the central portion 4 is substantially solid. After this form of blank has been hammered down by the swaging machine, it will be in the form shown in Fig. 13, and the results produced by the hammering operation upon the precious metal shell 2 will be the same as are produced upon the blank shown in Fig. 1. The ends 6 of the plug 5 are preferably tapered so as to completely fill the interior of the tubular core 1' when the blank is hammered down into the form shown in Fig. 11.

10 20 25 With the above described method of forming tapers the thickness of the precious metal shell can be varied in different portions of the taper as desired. The increase in thickness of said precious metal shell which takes place at the hollow portions of the blank can be varied as desired by changing the size of the hole or opening in such portions, and the decrease in thickness which takes place at the solid portions can be varied as desired by decreasing the diameter of the blank at this point or by not subjecting said

30 35 solid portions to the hammering operation.

While I have shown the invention as applied to a double taper, it will be understood that the blank shown in Fig. 1 can be cut through the central portion to form a

single taper of the character used in the manufacture of spectacle-temples.

What I claim as my invention and desire to secure by Letters Patent is:

1. An article of the class described comprising a tapered base metal core and a seamless precious metal shell covering said core, said precious metal shell being thicker at the reduced portion of said taper than at the enlarged portion thereof. 45

2. An article of the class described comprising a round base metal core tapered at each end and a seamless precious metal shell covering said core and extending the entire length thereof, said precious metal core being thicker at the end portions than at the 55 central portion.

3. The method of making articles of the class described which consists in forming a blank composed of a base metal core solid at one portion and hollow at another portion thereof, and covering said core with a seamless precious metal shell, and then reducing the hollow portion of said blank by a compressive action. 60

4. The method of making articles of the class described which consists in forming a blank composed of a tubular base metal core provided with an outer seamless precious metal shell, inserting a solid plug firmly in the central portion of said tubular core and 70 reducing down the end portions of said blank until the tubular end portions become practically solid. 70

RUDOLPH G. SCHUTZ.
